UNITED STATES PATENT OFFICE.

ALGERMONT H. WALDO, OF ST. PAUL, MINNESOTA.

DESIGN FOR A RUG.

Application filed December 4, 1922. Serial No. 4,480. Term of patent 3½ years.

To all whom it may concern:

Be it known that I, ALGERMONT H. WALDO, a citizen of the United States, residing at St. Paul, in the county of Ramsey and State of Minnesota, have invented a new, original, and ornamental Design for a Rug, of which the following is a specification, reference being had to the accompanying drawing, forming a part thereof, and wherein the figure is a plan view of a rug, showing my new design.

I claim:

The ornamental design for a rug, as shown.

In testimony whereof I have signed my name to this specification on this 29th day of November, A. D. 1922.

ALGERMONT H. WALDO.
